Enoch John West,
By his attorney,
James W. Smallman.

UNITED STATES PATENT OFFICE.

ENOCH JOHN WEST, OF FOLESHILL, ENGLAND.

BALL-BEARING FOR CYCLES.

SPECIFICATION forming part of Letters Patent No. 594,450, dated November 30, 1897.

Application filed November 23, 1896. Serial No. 613,143. (No model.) Patented in France November 25, 1896, No. 261,614.

To all whom it may concern:

Be it known that I, ENOCH JOHN WEST, cycle manufacturer, a subject of the Queen of Great Britain and Ireland, residing at Foleshill, near Coventry, in the county of Warwick, England, have invented certain new and useful Improvements in Ball-Bearings for Cycles and other Vehicles, (in respect whereof I have obtained French Letters Patent, No. 261,614, dated November 25, 1896,) of which the following is a specification.

This invention relates to ball-bearings for cycles and other vehicles and will be readily understood by reference to the accompanying drawings.

Figure 1 is a side elevation of the hub of a driving-wheel constructed according to the present invention. Fig. 2 is a corresponding right-hand end elevation. Fig. 3 is a longitudinal section showing the hub-shell, the fixed cup, the adjustable cup, and the split locking-ring, the cones and the spindle to which they are fixed being in side elevation. Fig. 4 is a side elevation of the adjustable cup. Fig. 5 is a left-hand end elevation of the adjustable cup. Fig. 6 is a side elevation of the split locking-ring. Fig. 7 is a left-hand end elevation of the split locking-ring.

Cup-adjusting ball-bearings for cycles usually have one cup firmly screwed home, and this cup is not touched for purposes of adjustment. The other cup is screwed up to the requisite extent and is then held by a lock-nut or other device. With a lock-nut two spanners are employed, one for adjusting the cup and holding it after adjustment and the other for tightening the lock-nut. The other devices, which can be tightened without displacing the adjusted cup, are complicated and expensive to manufacture.

My present invention consists of means for locking the adjusted cup, my object being to simplify the construction, to facilitate adjustment, and to produce a sure mode of concentric locking.

A is the spindle, and a and a' are the cones.

B is the shell of the hub, having a part b tapped with a right-hand thread and a part b', of larger diameter, tapped with a left-hand thread.

C is the fixed cup.

C' is the adjustable cup, screwing into the part b.

D is the split locking-ring, screwing into 55 the part b'.

Instead of the part b and the cup C' having right-hand threads and the part b' and the ring D left-hand threads the part b and the cup C' may have left-hand threads and the 60 part b' and the ring D right-hand threads.

The back of the cup C' has a cone c and flats c' and c''. The inside d of the split ring D is conical, (corresponding with the cone c on the adjustable cup C'), and outside the 65 ring there are holes d' and d''.

In order to adjust the bearing, the split ring D is unscrewed by a spanner having pins which engage with the holes d' and d''. The jaws of the spanner are then applied to the 70 flats c' and c'' and the cup C' is screwed up to the requisite extent. The pins are then again inserted in the holes d' and d'' and the locking-ring D is screwed home, the conical part d engaging with the cone c and gripping it 75 tightly. The tighter the cone c and conical part d are forced together the more the ring D will try to expand, and will consequently firmly grip the thread in the part b' of the shell of the hub. The tightening of the lock- 80 ring D does not disturb the adjustment of the cup C', as the ring and cup have opposite threads.

The drawings show a driving-wheel hub, but the invention may be applied to a front-wheel hub or to the bearings of the pedal-shaft or to pedal-bearings, as will be readily understood.

What I claim as my invention, and desire to secure by Letters Patent, is—

1. In a ball-bearing, the combination, with the shell of the bearing and an adjustable cup screwed in said shell and having a cone at the back thereof, of a split ring having a conical inside and screwed in the said shell, substantially as and for the purpose set forth.

2. In a ball-bearing, the combination, with the shell of the bearing and cones a and a' fixed on a spindle or shaft, of a cup C fixed in said shell, an adjustable cup C' screwed in the said shell and having a cone c on the back thereof, and a ring D having a conical inside d and screwed in the aforesaid shell, substantially as and for the purpose set forth.

ENOCH JOHN WEST.
